CONCRETE MIXER

Cecil Wheatley Stancliffe, Rochester, England,
assignor to Winget Limited, Rochester, England

Application February 17, 1942, Serial No. 431,234
In Great Britain February 22, 1941

6 Claims. (Cl. 259—154)

This invention relates to concrete mixers of the kind which are provided with means for delivering to mixing devices measured quantities of the materials, viz. aggregate, (usually separately in the form of fine aggregate or sand and coarse aggregate) cement and water, from hoppers or other containers.

Another object of the invention is to provide a concrete mixing machine in which the materials are delivered in measured quantities to a belt which carries them past agitators and to drive said belt by means which stop the belt when the amount of material in any of the hoppers or like containers falls to a predetermined amount or when the amount of mixed concrete in a container to which the machine may deliver reaches a predetermined value.

With these and other objects in view the invention consists in the improved combination of parts set out in the claims which follow.

The accompanying drawings show diagrammatically in elevation a concrete-mixing machine embodying the invention.

In these drawings Figs. 1 and 1a show the front part of the machine and Figs. 2 and 2a the back part.

The machine illustrated is similar to that described in specification No. 2,264,170 in which the gravel, sand and cement are deposited in layers on an endless belt and are then mixed dry by agitators past which the belt moves the material; water is then added and further mixing is effected by further agitators.

The invention is not, however, restricted to belt mixers but is applicable to all kinds having proportioning devices for the materials.

Referring to these drawings the belt is supported by roller chains A running between driving wheels B and return wheels C.

The gravel, sand and cement are deposited in measured quantities from hoppers D, E, F respectively and a dry mixing is effected by agitators G1 driven by bevel gearing from a horizontal shaft H; water is then delivered from a tank J and further mixing of the wetted materials is effected by agitators G2, G3 and G4.

The hoppers D, E, F carry flaps K1, K2, K3 on arms L1, L2, L3 connected to rods M1, M2, M3, arranged just above one of the roller chains.

The flaps K1, K2, K3 are normally held down by the weight of the materials 2 in the hopper but if in any hopper the material falls sufficiently low the rod M will fall and engage between the rollers of the chain A. A push-rod N with tappets P on

it is arranged above the roller; this push-rod is connected to the clutch Q through which the chain is driven.

A rod M4 is normally held in raised position by a ball R in the water tank so that if the water level falls to a predetermined amount the rod M4 will engage the chain.

If any one of the rods M falls it will engage the chain and therefore move forward with it; this will cause it to move the push-rod N forward through engagement with the tappet P thus throwing out the clutch Q and causing the chain and thus the conveyor belt to stop.

A fifth rod M5 is provided for control from the hopper or other container into which the mixed concrete is fed; when the container is full the rod M5 will drop and thus cause the mixing machine to stop; release of the rod M5 for stopping the machine is effected from the delivery point by electro-magnetic or other suitable means.

Means are preferably provided for throwing one or all the tappets through say an arc of 90 degrees by which means the automatic control is eliminated and the mixer becomes under manual control. In the latter case it is desirable that the clutch and the water flowing from the tank to the mixing belt shall be interlocked so that the stopping of the belt stops the water; but though the clutch and water delivery are interlocked, means are preferably provided whereby the water can be entirely stopped so that the belt alone can be caused to travel without any water flowing.

Means are preferably provided whereby on refilling any hopper or tank, which has caused the push-rod to throw out the clutch, its vertical rod is pulled out of the chain and this allows the clutch to be thrown in again by a suitable spring or weight.

In the apparatus above described the flaps act as mechanical relays by which the power of the belt is caused to control the clutch but similar flaps could also be used to operate electric contacts and thus give an electric control for stopping or starting the machine.

The invention is not restricted to the embodiments above mentioned but includes all arrangements or modifications coming within the ambit of the claims which follow.

I claim:

1. A concrete mixing machine having in combination containers for aggregate, cement and water, a belt, means driving said belt past said mixing devices, a roller chain driving said belt, rods arranged above said chain, means for causing one of said rods to fall into engagement with

the chain when the material of a container falls below a predetermined amount and means whereby said engagement causes the driving means of said chain to be thrown out of action.

2. A concrete mixing machine having in combination containers for aggregate, cement and water, a belt, means for delivering measured quantities thereof to the belt, mixing devices arranged above said belt, means for driving said belt past said mixing devices, a roller chain driving said belt, rods arranged above said chain, flaps in the containers for cement and aggregate normally holding said rods in raised position by the weight of material upon them in said containers, means for causing one of the rods to fall into engagement with said chain when its flap is released, and means whereby said engagement causes the driving means of said chain to be thrown out of action.

3. A concrete mixing machine having in combination containers for aggregate, cement and water, a belt, means for delivering measured quantities thereof to a belt, mixing devices arranged above said belt, means for driving said belt past said mixing devices, means for causing the belt to be stopped when the amount of any one of the materials in its container falls to a predetermined value, a roller chain driving said belt, a clutch driving said chain, a push-rod controlling said clutch and means for causing the push-rod to throw out the clutch when the amount of material in any of the containers reaches a predetermined value.

4. A concrete mixing machine having in combination containers for aggregate, cement and water, a belt, means for delivering measured

quantities thereof to the belt, mixing devices arranged above said belt, means for driving said belt past said mixing devices, a roller chain driving said belt, rods arranged above said chain, means for causing one of said rods to fall into engagement with the chain when the material of a container falls below a predetermined amount, a clutch driving said chain, a push-rod controlling said clutch, and tappets carried on said push-rod and engaged by said rods when moved into engagement with said chain.

5. A concrete mixing machine having in combination containers for aggregate, cement and water, a belt, means for delivering measured quantities thereof to the belt, mixing devices arranged above said belt, means for driving said belt past said mixing devices, a roller chain driving said belt, a floating ball lever carried in said water container, a rod connected to said ball lever and means for causing said rod to fall into contact with said chain and cause its driving means to be thrown out of action when the ball lever falls to a predetermined amount.

6. A concrete mixing machine having in combination containers for aggregate, cement and water, a belt, means for delivering measured quantities thereof to the belt, mixing devices arranged above said belt, a roller chain driving said belt, means for driving said chain, means controlled by the level of material in said containers, causing said chain to be positively engaged when the amount of any one of the materials in its container falls to a predetermined value, and means for stopping said driving means for said chain when said chain is so engaged.

CECIL W. STANCLIFFE.
